UNITED STATES PATENT OFFICE.

MICHAEL G. F. BUCKLEY, OF NEW YORK, N. Y., ASSIGNOR OF ONE-HALF
TO BENJAMIN F. SCHWARTZ, OF SAME PLACE.

PLASTER-BOARD.

SPECIFICATION forming part of Letters Patent No. 608,570, dated August 9, 1898.

Application filed October 19, 1897. Serial No. 655,730. (No model.)

To all whom it may concern:

Be it known that I, MICHAEL G. F. BUCKLEY, of New York city, county and State of New York, have invented an Improved Plaster-Board, of which the following is a specification.

This invention relates to a plaster-board which is of superior strength, can be readily applied to straight and curved surfaces, and will present extensive key-grooves to the mortar coating.

In the accompanying drawings, Figure 1 is a face view of my improved plaster-board; Fig. 2, a cross-section thereof, and Fig. 3 a similar section showing the board curved.

The letters *a a* represent a number of parallel rectangular slabs made of plaster-of-paris or other plastic material and connected by a continuous backing of woven-wire fabric *b*, embedded within the same. The slabs *a* are so arranged as to form open parallel spaces or slots *c* between them, within which the wire fabric *b* is exposed. These wired openings *c* thus constitute the joints between the slabs and also form key-grooves for gripping the usual mortar coating. Each slab *a* is provided with a short transverse arm *a'* of a length to extend half-way across the slot *c* and abut against a corresponding arm of the adjoining slab, the several pairs of arms *a'* being arranged to break joint.

The entire plaster-board formed as described may be rolled up and readily attached to the studding in a manner similar to wallpaper. It may with equal facility be attached to curved and straight surfaces, as the wired joints permit the board to assume a convex contour, Fig. 3. When applied to straight surfaces, the arms *a'* will form connecting-links between the slabs that greatly increase the rigidity of the structure. Finally, the extensive wired key-grooves between the slabs form such effective gripping-surfaces for the mortar that the latter may be applied without wetting and will adhere with increased tenacity.

What I claim is—

1. A plaster-board composed of a series of spaced slabs and of a common backing upon which the slabs are mounted and which is exposed between the slabs to form key-grooves, substantially as specified.

2. A plaster-board composed of a series of spaced parallel slabs, having laterally-projecting arms, and of a common wire backing upon which the armed slabs are mounted and which is exposed between the slabs to form wired key-grooves, substantially as specified.

MICHAEL G. F. BUCKLEY.
